LIGHTING FIXTURE

Gordon B. Hurlbut, Middlebury, Conn., assignor
to The Plume & Atwood Manufacturing Com-
pany, Waterbury, Conn., a corporation of
Connecticut

Application May 21, 1937, Serial No. 144,009

1 Claim. (Cl. 240—78)

This invention relates to illumination, and more particularly to lighting fixtures adapted to be suspended from a ceiling canopy or like support, and having means to adjust the position of a shade with respect to a lamp enclosed thereby.

One object of this invention is to provide a lighting fixture of the above nature comprising a pendant stem having a threaded section adjacent its lower end to receive an adjustable tapped bushing for supporting a combined lamp socket cover and shade support.

A further object is to provide a lighting fixture of the above nature provided with a flared sleeve loosely fitted upon the pendant stem and adapted to conceal any threads of said stem and bushing which would otherwise be exposed, thus enhancing the appearance of the lighting fixture.

A further object is to provide a lighting fixture of the above nature which will be simple in construction, inexpensive to manufacture, easy to manipulate, compact, ornamental in appearance, and very efficient and durable in use.

With these and other objects in view, there have been illustrated on the accompanying drawing, two forms in which the invention may be conveniently embodied in practice.

In the drawing:

Fig. 1 is an elevational view of one form of lighting fixture embodying the features of my invention.

Fig. 2 is a fragmentary longitudinal sectional view taken on the line 2—2 of Fig. 1.

Fig. 3 is a view in cross-section taken on the line 3—3 of Fig. 2, looking upwardly.

Fig. 4 is an elevational view of a modified form of lighting fixture also embodying the features of this invention.

Referring now to the drawing wherein like reference characters designate corresponding parts throughout the several views, the numerals 10 and 11 (Figs. 1 and 4) indicate ceiling canopies, from which are suspended pendant stems or tubes 12 and 13, respectively, said stems being preferably connected to said canopies by swivel joints 14 and 15. Each stem 12 and 13 is adapted to support a flared bell-shaped lamp socket cover 16, 17, from which a semi-indirect lighting bowl 18 is suspended by means of chains 19 (Fig. 1), and a globe 20 enclosing a bulb 21 (Fig. 4).

The tubular pendant stem 12 (13) is threaded for a substantial portion of its lower end, as shown at 22 in Fig. 2. At the extreme lower end of said stem, provision is made of a socket 24 having a flange 23 screwed on said threaded

portion. The socket is adapted to be held in adjusted position upon said stem 12, 13 by means of a set screw 25 threaded into a hub 26 extending upwardly from the flange 23 and engaging a flattened area 27 provided on said stem 12, 13, thus preventing rotation of the socket thereon.

The socket cover or bell 16, 17, is inturned at its closed upper end and provided with a circular aperture 28 loosely surrounding the threaded upper end 30 of an internally threaded adjustable bushing 29. The bushing 29 has an intermediate annular rib or flange 31 which serves as a support upon which the bell 16, 17 rests. The bushing 29 is also provided at its lower end with an unthreaded hub portion 32 through which passes a set screw 33 which is adapted to engage the threaded stem 12, 13, and to support the bell 16, 17 at any desired height.

The lamp bowl 18 and globe 20 respectively in both forms of the invention may thus be positioned correctly with relation to the lamps enclosed thereby.

In order to prevent rocking movements of the bowl holding bell 16 and globe holder 17, respectively, and to rigidly hold said members against the bushing 29 without rattling, provision is made of a locking ring nut 35 preferably knurled upon its periphery. The ring nut 35 is adapted to be screwed upon the threaded upper end 30 of the adjustable bushing 29 and serves to clamp the bell 16 or holder 17 against the supporting rib 31 of said bushing.

To conceal the exposed threads on the stem 12, 13, and on the top part of the bushing 29, which would otherwise be visible, provision is made of a short tubular sleeve 36, cylindrical at its top and flared at its lower end 37. The sleeve 36 is adapted to freely embrace the stem 12, 13 and the upper end of the bushing 29 and rest by gravity upon the upper surface of the ring nut 35. The ornamental appearance of the fixture will thus be greatly enhanced.

Operation

In operation, when it is desired to install the lamp bulb 21 held in the socket 24 in the correct position, the bowl 18, or globe 20, will first be removed. The ring nut 35 will then be loosened and the supporting bell 16 (or holder 17), the ring nut 35, and the concealing sleeve 36 will be slipped upwardly along the stem 12, 13, out of the way. The set screw 33 may then be loosened, and the bushing 29 rotated manually in the proper direction to adjust it lengthwise of the stem 12 or 13 as far as desired, whereupon the set screw 33

33 will be again tightened. The ring nut 35 will then be screwed down upon the bushing 29 and tightened to clamp the bowl 18 (or globe 20) against the annular rib 31,—the sleeve 36 being 5 permitted to drop by gravity upon the ring nut 35, in which position it will effectively cover the exposed threads on the stem 12, 13, and the upper end 30 of the bushing 29.

While there have been disclosed in this specification two forms in which the invention may be embodied, it is to be understood that these forms are shown for the purpose of illustration only, and that the invention is not to be limited to the specific disclosures, but may be modified 10 and embodied in various other forms without departing from its spirit. In short, the invention includes all the modifications and embodiments coming within the scope of the following claim.

Having thus fully described the invention, what 15 is claimed as new, and for which it is desired to secure Letters Patent, is:

In a lighting fixture, a supporting stem depending from a ceiling canopy, said stem having

an exterior threaded portion of substantial length adjacent its lower end, a lamp socket mounted on the lower end of said stem and detachably secured against translation and rotation with respect thereto, an adjustable bushing 5 screwed on said threaded portion, said bushing being exteriorly threaded at its upper end, a set screw passing through said bushing for detachable engagement with said threaded portion to lock said bushing at any desired height, said bushing having outstanding means intermediate its ends, a hollow shade holder surrounding said stem and lamp socket and having its upper end resting on said outstanding means, a locking nut 10 screwed on the upper part of said bushing for clamping said holder against said outstanding means, and an elongated sleeve flared at its lower end loosely fitted upon said stem and resting by gravity upon said locking nut, said sleeve 15 extending upwardly beyond the threaded portion 20 of said stem and serving to conceal the threads of said stem and said bushing.

GORDON B. HURLBUT.
